DESIGN FOR A HOLDER FOR TOILET ARTICLES

Robert W. Dailey, Chicago, Ill., assignor to La
Vall, Inc., Chicago, Ill., a corporation of Illinois

Application July 21, 1933. Serial No. 48,778

Term of patent 3½ years

To all whom it may concern:

Be it known that I, ROBERT W. DAILEY, a citizen of the United States, residing at the city of Chicago, in the county of Cook and State of Illinois, have invented a new, original, and ornamental Design for a Holder for Toilet Articles, of which the following is a specification, reference being had to the accompanying drawing, forming a part thereof.

In the drawing, Figure 1 is a top plan view, Figure 2 a side elevational view and Figure 3 an end elevational view of a holder for toilet articles, showing my new design.

I claim:

The ornamental design for a holder for toilet articles as shown.

ROBERT W. DAILEY.
